(57) CLAIM

The ornamental design for a wedge type golf club head, as shown and described.

DESCRIPTION

FIG. 1 is a back view of the wedge type golf club head as claimed herein;

FIG. 2 is a front perspective view of the golf club head thereof;

FIG. 3 is a front view thereof;

FIG. 4 is heel end view thereof;

FIG. 5 is a toe end view; and,

FIG. 6 is a cross section taken on line 6—6 of FIG. 2. The broken line showing is for illustrative purposes only and forms no part of the claimed design.
